US0D1046692S

(12) **United States Design Patent** (10) **Patent No.:** **US D1,046,692 S**
(45) **Date of Patent:** **** Oct. 15, 2024**

(54) **MOTORCYCLE**

(71) Applicant: **NANJING VMOTO
MANUFACTURING CO, LTD,**
Nanjing (CN)

(72) Inventor: **Yiting Chen**, West Perth (AU)

(73) Assignee: **Nanjing Vmoto Manufacturing Co,
Ltd**, Nanjing (CN)

(**) Term: **15 Years**

(21) Appl. No.: **29/870,430**

(22) Filed: **Jan. 26, 2023**

(30) **Foreign Application Priority Data**

Jul. 28, 2022 (CN) 202230487245.7

(51) **LOC (14) Cl.** **12-11**

(52) **U.S. Cl.**

USPC **D12/110**

(58) **Field of Classification Search**

USPC D12/110, 111, 117; D21/432, 538

CPC B62K 11/00; B62K 11/02; B62K 11/04;
